Patented Jan. 13, 1920.

Inventor

Sakyo Yai,
By
B. Singer, Attorney

UNITED STATES PATENT OFFICE.

SAKIZO, OF TOKYO, JAPAN.

DRY BATTERY.

1,328,027.

Specification of Letters Patent. Patented Jan. 13, 1920.

Application filed January 30, 1919. Serial No. 274,070.

To all whom it may concern:

Be it known that I, SAKIZO YAI, a subject of the Emperor of Japan, and a resident of No. 2, 1-Chome, Nishiki-Cho, Kanda-Ku, 5 city of Tokyo, Empire of Japan, have invented new and useful Improvements in Dry Batteries, of which the following is a specification.

This invention relates to improvements in 10 electric batteries of the dry cell type, and relates more particularly to the means of providing a tight joint between the inner wall of the outer casing and the gun material with which the open end of the outer 15 casing is to be closed.

The invention consists in the construction, combination and arrangement of devices hereinafter shown and described.

The accompanying drawing is an elevation, 20 partly in vertical central section, of a dry battery constructed and arranged in accordance with my invention.

The outer casing 1 contains the mixture 2 of carbon and hydrogen absorbing material, such for instance, as a mixture of graphite and manganese peroxid. The lining 3 is of material which is adapted to absorb liquid and the negative plate 4 is placed within the black mixture 2.

30 The seal of gum material, preferably as-

phalt, which closes the open end of the outer casing is in accordance with my invention, formed with a circumferential flange 5^a which extends therebeyond. The wall of the container is bent against the under and peripheral sides of the said flange 5^a, as at 6₁ and is also bent inwardly against the upper side of the seal to partially overlap the same, as shown. Such construction forms a groove in the diametrically enlarged open end portion of the said container wall and in which groove the flange of the seal is contained so that a tight joint is formed between the seal and the container wall.

Having thus described my invention, I 45 claim:—

In a dry battery, a container, a mix therein, and a seal for the container, said seal having a circumferential flange extending therebeyond, and the wall of said container 50 being bent to bear against the under and peripheral side of the said flange and also against the upper side thereof and to partially overlap the same.

In testimony whereof I affix my signature 55 in presence of two witnesses.

SAKIZO YAI.
